DIAL ENGRAVING MACHINE

Howard A. Satterlee, Needham, Mass., assignor to
 Submarine Signal Company, Boston, Mass., a
 corporation of Maine.

Application June 28, 1937, Serial No. 150,769

14 Claims.

(Cl. 33—19)

The present invention relates to engraving machines and more particularly to machines for engraving the divisions on a dial.

A plan view of the machine is shown in Fig. 1 of the drawings and a front elevation partly in section in Fig. 2; Fig. 3 is a sectional view along the line III—III in Fig. 2; Fig. 4 is an enlarged cross sectional view of the cutting head along the line IV—IV in Fig. 2; Fig. 5 is an enlarged cross sectional view along the line V—V in Fig. 2; Fig. 6 is an enlarged partial section along the line VI—VI in Fig. 2; and Fig. 7 is an enlarged cross sectional view along the line VII—VII.

As shown in the drawings a plate or dial 1 which is to be engraved is mounted upon a table 2, being centered thereon by the stud 3 and securely clamped by means of the disc 4 and the wing nut 5. Radial graduations 6 are cut in the dial by the reciprocating motion of a cutting head 7 carrying the cutting tool 8, the dial being automatically advanced by the proper angular distance after each stroke of the cutter head.

The entire mechanism is mounted upon a base member 9. Power for operating the machine is supplied by the motor 10 through the gears 11 and 12, the latter being fixed to a shaft 13 journaled in a bearing at the top of the base. At the upper end of the shaft 13 there is mounted an eccentric cam 14 to which is attached a link 15 by means of the stud 16 and the nut 17. The link 15 is at its opposite extremity joined to the bar 18 by means of the stud 19 and the nut 20. The bar 18 is fixed to the member 21 which contains a latch mechanism to be described later. The member 21 is fixed to a ram 24 adapted to slide in a groove 22 formed in the ram guide 23 which is preferably made integrally with the base 9. The ram 24 is retained in the groove by means of the members 31 and 32 which are fixed to the ram guide 23. The ram 24 is substantially the same length as the ram guide 23.

A stud 25 is mounted in the side of the ram 24 and forms a pivot bearing for the cutter head support 26, the latter being secured by means of the nut 27. Also secured to the ram 24 is a pin 28 which projects into the cutter head carrier 26 through an elliptical aperture. Pressing against the pin 28 is a coil spring 29 mounted in a vertical hole in the bottom of the cutter head carrier 26 and held therein by means of the set screw 30. This spring always tends to press the left-hand end of the cutter head support downward and consequently tends to raise the cutter head 7. The downward motion of the left-hand end 28 of the cutter head carrier is limited by the size

of the aperture in which the pin 28 moves and is made sufficient to raise the cutter head well above the work being engraved.

The ram guide 23 also carries the pin 33 near its forward upper edge. The latter is adapted to engage a detent 34 mounted on the top of the cutter head carrier 26 and brings about a depression of the cutter head at the end of its backward stroke, whereby the cutter 8 is placed in cutting position.

The cutter head carrier 26 is held in cutting position during its forward stroke by the latch mechanism above referred to. This consists of a pin 35 mounted in the end of the cutter head carrier 26, which pin is engaged by the end 36 of the latch rod 37 slidably mounted in the sleeve 38 which is fixed to the member 21. The latter has a hollow portion through which the rod 37 passes. Surrounding the rod within this hollow portion is a spring 39 whose left-hand end bears against the left wall of member 21 and whose right-hand end bears against a collar 40 on the rod 37. The spring thus exerts a pressure on the rod 37 tending to force it outward to the right so that the portion 36 engages the pin 35 of the cutter head carrier, thereby holding the latter in cutting position against the pressure of spring 39.

At the left end of the rod 37 there is mounted a dog 41 which is adapted to engage one or more of the discs 42 which can best be seen in Fig. 6. The latter are mounted on a stud 43 fixed in a shoulder 44 of the ram guide 23. The discs 42 have notches 45 cut in them in various positions to permit the dog 41 and consequently the rod 37 to travel in a forward direction various desired distances before releasing the pin 35, in order to permit adjustment of the length of stroke of the cutter 8. The discs 42 are held in position on the stud 43 by a pin 46 which is fixed to a ratchet 47.

The ratchet and discs may be clamped against a shoulder 48 on the stud 43 by means of a wing nut 49. The disc and ratchet assembly is rotated through a desired angle for each stroke of the cutter head by means of a pawl 50. The latter is fixed by the pin 51 to the bell crank 52 which is pivoted on the stud 43 and carries on its lower arm a pin 53. The pin 53 is engaged by the fork formed by the pins 54 and 55 set in the end of the arm 56 fastened to the hollow shaft 57. The latter is fixed to another arm 58. The two arms 56 and 58 together with the shaft 57 are rotatably mounted on a stud 59 which is fastened to the base. Oscillatory motion is transmitted to the arm 58 by means of a roller 60 which rotates on the stud 51 fixed to the arm 58 and is driven 59

by frictional contact with the eccentric driving cam 14. In order to secure proper contact between the cam and the roller a spring 62 is provided to press the roller 60 against the cam 14.

5 A similar cam and roller system serves to rotate the dial-supporting table 2 through the desired angle between graduations. This system comprises the roller 63 which is also driven by the cam 14 and rotates about the stud 64 fixed 10 to the arm 65. The roller 63 is pressed into contact with the cam 14 by means of the springs 66. The arm 65 is fixed to a hollow shaft 67 whose other end carries the arm 68, the assembly of the two arms and hollow shaft being arranged 15 to rotate on the stud 69 fixed to the base. Two pins 70 and 71 mounted in the end of the arm 68 form a fork which engages the pin 72 fixed in the end of one arm of the bell crank 73, the other arm of which carries the pawl 74 which engages the ratchet 75. The latter is fixed to a shaft 76 but the bell crank 73 is free to rotate on this shaft. One end of the shaft is journaled in a bearing in the support 77 fixed to the base, the other end being journaled in bearings in the 20 support 78 beneath the table 2. Between the crank 73 and the ratchet 75 there is provided a cam 79 which is free to be turned on the shaft 76. It is held in desired positions by a locking screw 80 which projects through an aperture 81 in the support 77. As shown in Fig. 5, the cam 79 has a cutaway portion which permits the pawl 25 74 to engage the ratchet 75 for a definite number of teeth depending upon the cam position.

Rotation of the shaft 76 is transmitted to the 30 table 2 by means of the worm gear 82 and a pinion 83 fixed to a boss 84 on the table 2 by means of the screws 85 which are threaded into a disc 86. A shaft 87 is firmly fixed to the table 2 and terminates above it in the stud 3. The shaft 87 35 serves to center the gear 83 and the disc 86 as well as a similar disc 88 which has a shoulder 89. The joint between the discs 86 and 88 is carefully lapped to provide an accurate bearing so that the table 2 will always remain and rotate in a fixed plane. The disc 88 on its lower side has a shoulder 90 which passes through the base 9. At the lower end of the shoulder 90 a thrust-bearing screw 91 is screwed into the shaft 87 and bears against the lower surface of the shoulder 90, thereby pressing the disc 88 against the disc 50 86.

In order to adjust the position of the table 2 with respect to the cutter 8 to care for varying diameters of dials, a longitudinal adjustment of the table is provided. This comprises a longitudinal slot in the base 9 in which is fitted a rectangular shoulder 92 forming part of the plate 89. This shoulder 92 is closely fitted in the slot in the base 9 to provide an accurate guide 55 for longitudinal motion of the table. The table is locked in position by means of a disc 93 bearing against the base 9 by four screws 94, pressure being applied by the ring 95 threaded on the exterior of the shoulder 90. A handle 96 may be 60 provided for conveniently locking and unlocking the threaded ring 95. In order to permit longitudinal adjustment of the table the shaft 76 is provided with a longitudinal groove 97 in which internal tongues in the bearings and in the worm gear 82 can slide. All looseness between the worm 82 and the gear 83 is avoided by means 65 of an adjusting screw 98 in the plate 89 which controls the position of the bearing support 78. 70

75 Adjustment of the cutter 8 to give the proper depth of cut with varying thicknesses of material

is provided by the arrangement shown in Fig. 4. The cutter 8 is provided with a forked upper portion 100 which passes around the neck of the adjusting screw 101 threaded into the cutter head 7 and held against motion by the set screw 102 5 as shown in Fig. 4.

The operation of the machine is as follows: Let us assume that the proper adjustments have been made and that a disc of material 1 to be engraved is secured to the table 2. Further assume that the cutter head carrier 26 is in its extreme left-hand position. In this position the pin 33 will have engaged the detent 34, depressing the cutter 8 below the upper surface of the material and at the same time raising the left 10 end of the cutter head carrier including the pin 35. This will have permitted the latch 36 to pass below the pin 35 whereby the cutter will be maintained in cutting position. As the motor revolves, the cutter head carrier 26 is forced 15 forward by power transmitted to it through the link 15 and the bar 18 so that the cutter 8 engages and cuts the dial to be engraved. When the dog 41 strikes one of the discs 42, the continued forward motion of the ram 24 and the 20 member 21 causes the latch 36 to be drawn into the member 21 and therefore to release the pin 25 22 so that under the action of the spring 29 the cutter-carrying end of the member 26 is forced upward withdrawing the cutter 8 from the material 1. Since at this time the cutter 8 is still moving in a forward direction, it will take a smooth upward tapering cut, thereby cleaning 30 all chips out of the cut. Forward motion of the cutter head continues until the central position 35 of the eccentric shaft 16 is reached, at which time the link 15 begins to pull the bar 18 and the cutter head assembly back.

While the cutter head has been advancing, the bell crank 73 has been rotated through a certain angle, counter-clockwise as shown in Fig. 5, 40 by the motion of the arm 68 through the roller 63. This motion of the bell crank 73 carries the pawl 74 downward along the ratchet 75.

In a similar manner the bell crank 52 will have carried the pawl 50, clockwise as shown in Fig. 5, 45 along the ratchet 47.

During the backward travel of the cutter head assembly the bell crank 73 will be turned clockwise as seen in Fig. 5, causing the pawl 74 to engage the ratchet 75 and turn it through a certain angle. This rotates the shaft 76 and the worm 82, thereby causing a rotation of the table 2 through a definite angle to place it in the proper position for the second cut. At the same 55 time the bell crank 52 will have rotated the ratchet 47 through the pawl 50 through a certain angle, thereby advancing the position of the disc assembly 42.

The sequence of operations is then repeated. 60

Adjustment of the angle, through which the plate 2 is turned and therefore of the spacing between successive graduations cut in the dial, is made by adjusting the number of teeth in the ratchet 75 which are engaged by the pawl 74. 65 This is done by rotating the cam 79 by means of the adjusting screw 80 into such a position that only the desired number of teeth of the ratchet are exposed to the action of the cam. The shape of the cam 79 can clearly be seen in Fig. 5. Further adjustment can be made by changing the 70 number of teeth in the ratchet 75 or the ratio between the worm 82 and the gear 83.

For most purposes it is desired to graduate the dial in such a manner that each tenth cut is con- 75

siderably longer than the divisions between while each fifth cut is intermediate in length. This or any other desired sequence of lengths of successive cuts is obtained by the arrangement of the discs 42 and the number of teeth in the ratchet 47. For a long stroke of the cutter 8, the outer discs 42 are cut away to permit the dog 41 to travel as far as the inner disc as shown in Fig. 6. For a shorter length of cut, the first disc is cut away so that the dog will strike the second of the discs, while for a very short cut the dog is arranged to strike the outermost of the three discs. By suitable spacing of the cuts in the discs and suitable variations in the thicknesses of the discs in association with the proper number of teeth on the ratchet 47 and the angle of motion of the pawl 50, any desired combination of lengths of cuts can be obtained.

A handwheel 103 on the end of the driving motor shaft provides flywheel action and further is of particular value in making possible manual operation of the machine whereby accurate adjustment of the proper depth of the cutter can readily be made. The depth of cut is conveniently indicated by graduation on the top of the cutter-adjusting screw 101 and the index 104.

By the use of the present machine, dials can easily be calibrated by degrees around the whole circumference in one minute or less.

30 Having now described my invention, I claim:

1. A dial-engraving machine including a cutter, means for moving the same over the dial in a succession of cutting strokes of constant length and means for raising the cutter out of the dial 35 during each cutting stroke when the desired length of cut has been made.

2. A dial-engraving machine including a cutter, means for moving the cutter radially over the dial in a cutting direction, means for delimiting the length of cut including means for depressing the cutter below the surface of the dial at the beginning of the cutting stroke and means for raising the cutter out of the dial when the desired length of cut has been made and while the cutter is still moving in the cutting direction.

45 3. A dial-engraving machine including a cutter, means for reciprocating the cutter over the dial in a radial direction, means for depressing the cutter to take a cut from the edge of the dial toward the center and means for raising the cutter out of the dial when the desired length of cut has been made and while the cutter is still moving toward the center of the dial.

4. In a dial-engraving machine, a cutter, means 55 for moving the cutter radially over the dial in a cutting direction, means for delimiting the length of cut including means for depressing the cutter below the surface of the dial at the beginning of the cutting stroke, latch means for holding the cutter in cutting position and means for releasing the latch and raising the cutter when the desired length of cut has been made.

5. A dial-engraving machine comprising means 65 for supporting the dial to be engraved, a cutter, means for reciprocating the cutter radially over the dial, means for delimiting a portion of the cutter's stroke in which a cut is taken, means cooperating with the reciprocating means for withdrawing the cutter from the material in other portions of the cutter's stroke and means 70 synchronized with said reciprocating means for advancing the dial by a predetermined angular deviation after each cutting stroke.

6. A dial-engraving machine including a cutter, means for rapidly and continuously recipro-

cating the cutter radially over the dial, means for depressing the cutter below the dial surface at the beginning of the cutting stroke and before the cutter's engagement with the dial, means for raising the cutter out of the dial when the desired length of cut has been made and while the cutter is still moving in the cutting direction and means synchronized with the cutter reciprocating means for rotating the dial through a predetermined angle to place it in position for the next cut while the cutter is being returned to its initial position.

7. A dial-engraving machine including a cutter, a rotatable table for supporting the dial to be engraved in position to be engaged by said cutter, means for reciprocating the cutter radially over the dial and means for advancing the table through a predetermined angle corresponding to the number of graduations to be cut in the dial including a ratchet, a pawl adapted to engage the ratchet, means for transmitting motion of the ratchet to the table, means synchronized with the cutter reciprocating means for oscillating the pawl through a fixed angle and means for selectively varying the number of ratchet teeth engaged by the pawl in its oscillations.

8. A dial-engraving machine including a rotatable table for supporting the dial to be engraved, a cutter, means for reciprocating the cutter radially over the dial, and means for advancing the table through a predetermined angle after each cutting stroke comprising a gear fixed to the table, a shaft, a worm fixed to said shaft and adapted to mesh with said first gear, a ratchet fixed to said shaft, a bell-crank, means synchronized with the cutter-reciprocating means for oscillating said crank through a fixed angle and a pawl mounted on one arm of said crank and positioned to engage said ratchet.

9. A dial-engraving machine including a rotatable table for supporting the dial to be engraved, a cutter, means for reciprocating the cutter radially over the dial, and means for advancing the table through a predetermined angle after each cutting stroke comprising a gear fixed to the table, a shaft, a worm fixed to said shaft and adapted to mesh with said first gear, a ratchet fixed to said shaft, a bell-crank, means synchronized with the cutter-reciprocating means for oscillating said crank through a fixed angle, a pawl mounted on one arm of said crank and positioned to engage said ratchet, a cam having a diameter at least as large as that of said ratchet and being loosely mounted on said shaft adjacent to the ratchet, said cam having a cut-away peripheral portion of a length corresponding to the angle of oscillation of said pawl, the latter having sufficient width to engage both said ratchet and said cam and means for adjusting the angular position of the cut-away portion of said cam to determine the number of teeth of the ratchet engaged by the cam in each oscillation thereof.

10. A dial-engraving machine including a cutter, means for reciprocating the cutter over the dial in a radial direction, means for depressing the cutter to take a cut from the edge toward the center of the dial including a latch mechanism to hold the cutter in cutting position, means for releasing the latch and raising the cutter out of the dial when the desired length of cut has been made including a dog forming part of the latch mechanism and mounted on the cutter-reciprocating means, a plurality of discs positioned to be engaged by said dog for the release of the latch during forward motion of the cutter and having

- 5 a combined thickness corresponding to the shortest line to be engraved, said discs being notched at their peripheries to present varying combined disc thickness to the dog whereby the latch is released at corresponding lengths of cut and means 10 for rotating said disc assembly with respect to said dog through a selected angle after each cutting stroke of the cutter.
11. A dial-engraving machine including a cutter, means for continually reciprocating the same radially over the dial in a constant length of stroke, means for depressing the cutter below the surface of the dial at the beginning of the cutting stroke and means for raising the cutter out 15 of the dial during each cutting stroke when the desired length of cut has been made.
12. A dial-engraving machine including a cutter, means for continually reciprocating the same radially over the dial in a constant length of stroke, means for depressing the cutter below the surface of the dial at the beginning of the cutting stroke, means for raising the cutter out of the dial during each cutting stroke and adjustable means for controlling the point of operation 20 of said cutter-raising means in successive strokes whereby the lengths of successive lines can be controlled in accordance with a predetermined schedule.
13. A dial-engraving machine including a cutter, means for continually reciprocating the same radially over the dial in a constant length of stroke, means for depressing the cutter below the surface of the dial at the beginning of the cutting stroke, means for raising the cutter out of the dial during each cutting stroke and means for controlling the point of operation of said cutter-raising means in successive strokes whereby the 25 lengths of successive lines can be controlled in accordance with a predetermined schedule. 5
14. A dial-engraving machine including a cutter, a cutter head, a cutter-head carrier, a reciprocating ram, means pivoting the cutter-head carrier on said ram on an axis perpendicular to the direction of motion of the ram and parallel to the surface being engraved, a pair of stops limiting the angular motion of the cutter-head carrier on said pivot to a small angle, means normally tensioning the cutter-head carrier against one of said stops, means locking the cutter-head carrier against the other of said stops when a cut is to be made and means for controlling for each succeeding reciprocation of the ram the operation of said locking means whereby the 20 lengths of successive cuts can be controlled. 25

HOWARD A. SATTERLEE.
